UNITED STATES PATENT OFFICE.

HARRY P. BRAISTED, OF WOODMONT, CONNECTICUT, ASSIGNOR TO THE JOHN HUGO MANUFACTURING COMPANY, OF NEW HAVEN, CONNECTICUT, A CORPORATION OF CONNECTICUT.

DESIGN FOR A TOY.

Application filed January 13, 1923. Serial No. 4,880. Term of patent 7 years.

To all whom it may concern:

Be it known that I, HARRY P. BRAISTED, a citizen of the United States, residing at Woodmont, county of New Haven, State of Connecticut, have invented a new, original, and ornamental Design for Toys, of which the following is a specification, reference being had to the accompanying drawing, forming part thereof.

The figure of the drawing is a side elevation of a toy, showing my new design.

In this drawing the surface markings for the different zones or spaces indicated are intended to show merely that the adjacent zones or spaces are of contrasting colors.

I claim:

The ornamental design for a toy, substantially as shown and described.

HARRY P. BRAISTED.
